of America, a corporation of Delaware

Application April 27, 1936, Serial No. 76,633

12 Claims. (Cl. 164—20)

This invention relates to apparatus for serially blanking out sections of material for use in the interior of automotive vehicle bodies. More particularly, it relates to a machine which may be conveniently utilized for the purpose of blanking out sections of padding for inner trim panels or for blanking out sections of upholstery finish material, as may be desired.

In order to obtain a more complete understanding of the invention presented in this application, reference may be had to applicants' prior co-pending application Serial No. 71,515, filed March 28, 1936, in which is illustrated and described the complete assembly line of which the unit disclosed and claimed herein forms one specific part.

The present invention contemplates the provision of continuously operated apparatus for feeding an endless web of material to a point adjacent a blanking out press. Novel and improved mechanism is provided in order to arrest movement of the material at this point and to intermittently feed the same through a blanking press in order that the material will be maintained stationary during the stamping operation.

The broad inventive concept presented in this application will find practical utility in many and varied different applications, but it will be appreciated that the present disclosure relates specifically to two primary uses for which the apparatus shown is intended. The apparatus may be utilized in connection with a pad generating unit of such structure that a substantially continuous, loosely felted web of non-woven fibrous material is fed to the blanking press and the apparatus, when used for this purpose, will serve to blank out sections of this web which may subsequently be applied to relatively stiff backing sheets and then covered with fabric finish material to form inner trim panels for automobiles. The apparatus disclosed will also find practical utility in combination with an upholstery forming machine which serves to generate a continuous composite strip comprising upper and lower fabric layers having padding material secured therebetween by means of longitudinally disposed lines of stitching. Sections of this strip may be blanked out to form pieces of upholstery of a configuration particularly adaptable for finishing automobile seat backs and seat cushions.

The present invention contemplates the provision of novel mechanism for continuously feeding a web to be blanked out to a point adjacent a blanking press and of novel means for intermittently feeding the web through the blanking press whereby the resultant speed of the inter-

mittent feed is accurately and definitely controlled with respect to the rate of delivery of the constant feed mechanism.

The invention further contemplates the provision of novel means for feeding the padding material in between the dies of the press, which mechanism serves also to aid in ejecting the sections of material after the blanking out operation has been completed.

Many other and further objects and advantages of the present invention will become clearly apparent from the following specification when considered in connection with the accompanying drawings forming a part thereof.

In the drawings:

Figure 1 is a fragmentary plan view of a section of loosely felted, non-woven fibrous material, illustrating the manner in which sections thereof are blanked to form;

Fig. 2 is a plan view of a section of padding material blanked to a configuration for use in an inner trim panel;

Fig. 3 is a transverse, sectional view, taken substantially on the line 3—3 of Fig. 2;

Fig. 4 is a fragmentary, perspective view, with portions broken away, illustrating one embodiment of the apparatus of the present invention utilized for the purpose of blanking out padded sections for inner trim panels;

Fig. 5 is a longitudinal, vertical, sectional view, taken substantially on the line 5—5 of Fig. 4, illustrating the interior construction of the blanking press;

Fig. 6 is a fragmentary plan view of a continuous strip of upholstery material illustrating the manner in which sections may be blanked to form by the improved apparatus of the present invention;

Fig. 7 is a plan view of a section of upholstery material blanked out to predetermined desired configuration for use in a seat back;

Fig. 8 is a transverse, sectional view, taken substantially on the line 8—8 of Fig. 7, illustrating in detail the interior construction of the upholstery strip; and

Fig. 9 is a fragmentary, perspective view of an embodiment of the invention, illustrating the apparatus designed for blanking out sections of upholstery material from a continuous web.

With more particular reference to the drawings, the specific embodiment of the invention illustrated therein is, as has been described above, primarily adapted for use in preparing inner trim materials for automotive vehicles. In the form of the invention illustrated in Figs. 4 and 5

5 it will be appreciated that the apparatus is intended for use in the manufacture of pre-formed sections of padding material to be used in the construction of padded inner trim panels. 5
 5 As will be understood by reference to applicants' assignee's prior co-pending application referred to above, means are utilized in connection with the apparatus of Fig. 4 for delivering a substantially continuous strip of loosely felted, non-woven fibrous padding material to a point adjacent the blanking out press. Inasmuch as this web of padding material is continuously generated, it is inherent that the delivery thereof to the blanking press will be at a substantially uniform and constant rate of speed. While this delivery may be accomplished in any manner such as may be desired, the apparatus of the present invention contemplates the utilization of a conveyor comprising a pair of continuous chains 10 interconnected by transversely extending rods 11 which serve to support a continuous web of padding material 15. These chains pass over suitable sprocket wheels 12 which are journaled upon a shaft 13 mounted 10 for rotation in a supporting framework 14 adjacent the blanking press hereinafter described in detail. A sprocket wheel 16 is secured to the shaft 13 and serves, by means of a sprocket chain 17, to drive a sprocket wheel 18 which is secured to the shaft of a roller 19 over which passes an endless conveyor belt 20 which serves to receive the web of padding material 15 and feed the same to the blanking press. The upper run of the endless conveyor belt 20 extends from the roller 19 to a roller 21 journaled for rotation in the framework 22 of the blanking press. 15
 20
 25
 30
 35

This roller 21 is intermittently operated as will hereinafter be described in detail in order to intermittently feed the padding material from the conveyor into the blanking press. The lower run of the conveyor belt 20 extends downwardly from the roller 21 and passes underneath an idle roll 24 journaled for rotation in suitable brackets 25 secured to the floor on which the apparatus is mounted. The conveyor belt 20 then passes upwardly over an idle roller 26 journaled for rotation in the framework 14 and downwardly around a take-up roll 27 which is mounted for vertical movement in guides 28 constituting a part of the framework 14. 40
 45
 50

From the foregoing description it will be appreciated that as the roller 19 is constantly driven by means of the feed conveyor, the upper run of the conveyor belt 20 will be uniformly fed forwardly by the roller 19 at a rate substantially the same as the rate at which the fibrous web of padding material 15 is delivered thereto. Inasmuch as the roller 21 is intermittently driven as hereinafter described, it will be appreciated that the upper run of the conveyor belt 20 will gradually sag downwardly to substantially the position shown in Fig. 4, as this drive takes place. The downward movement of the central portion of the upper run of the conveyor belt 20 will be permitted due to the vertically movable take-up roll 27 mounted in the guides 28 and it will be seen that, as this portion of the conveyor belt sags downwardly, this roller 27 will be raised vertically in its guideways. A compacting and feed roll 30 may be journaled for rotation in the framework 14 in a position to cooperate with the roller 19 in order to positively feed the web of fibrous material onto the conveyor 20. 55
 60
 65
 70
 75

The blanking press includes the base frame 22, to each of the lateral sides of which are secured

suitable upwardly extending side frame members 35. A lower die bed 36 is secured in stationary position on the base frame 22 and it will be seen that the web of fibrous material is fed over the surface of this bed by means of the conveyor 20. The roller 21 at the forward end of the conveyor 20 preferably has a feed roll 37 cooperating therewith in order to effect a positive feed of the fibrous material over the bed 36 of the press. An upper die 38 of a configuration adapted to cooperate with the bed 36 to blank out sections of padding material of the desired configuration, is mounted in a suitable die retainer 39 permanently secured to a movable framework 40 supported by a plurality of vertically extending operating rods 41, one pair of which is located at each of the lateral sides of the conveyor. These operating rods 41 preferably extend through suitable apertures in the bed of the press and are all permanently secured at their lower ends in a movable actuating frame 42 disposed interiorly of the base frame 22. 5

 65
 70
 75

A shaft 45 is journaled for rotation in the base frame 40 of the blanking press and has a pair of eccentrics 46 permanently secured thereto. Cooperating members 47 are mounted for rotation on the peripheral surfaces of the eccentrics 46 and have projecting portions 48 which serve to provide means for pivotally mounting links 49. The outer ends of the links 49 each have pivotally secured thereto a pair of links 50 which serve to interconnect the outer ends of the links 49 with the actuating framework 42, and the links 49 also have pivotally secured thereto links 51 which support the outer ends of the links 49 on suitable permanently mounted projecting brackets 52 shown as formed integrally with the base frame 22. This link assembly serves to provide a toggle construction which, upon rotation of the shaft 45, serves to effect vertical movement of the actuating framework 42 and which consequently serves to move the die 38 into engagement with the bed 36 to blank out a section of padding material to the desired configuration. 30

 70
 75

The shaft 45 which serves to actuate the movable die 38 has connected to the outer end thereof a large gear 60 which is adapted to be driven by an electric motor 61 operating through a suitable sprocket chain 62 and clutch mechanism 63 hereinafter described in greater detail. 45
 50
 55
 60
 65
 70
 75

It will be appreciated from the foregoing that when the clutch mechanism 63 is engaged, the electric motor will serve to drive the large gear 60 and consequently effect an engagement of the dies 36 and 38 to blank out a section of padding material to the desired configuration, and it will be further appreciated that one revolution of this shaft 45 will serve to complete one cycle of movement of the blanking press. The clutch mechanism 62 is preferably constructed by means conventional in the art in such a manner that when it is engaged it will automatically be disengaged upon the completion of one complete cycle of operation of the die press. 55
 60
 65
 70
 75

A pair of cylindrical, substantially vertically disposed housings 65 are connected in unit relation by means of a transversely extending connecting bar 66. This connecting bar 66 is guided for vertical movement by a pair of forked depending brackets 67 secured to the underside of the transversely extending frame member 68 connecting the upper ends of the side frames 35 with the blanking press. A pair of threaded rods 69 each have their lower ends secured to the transversely extending connecting bar 66 and pass up- 65
 70
 75
 80
 85
 90
 95

wardly through the brackets 67 and frame member 68 and each threadably has secured thereon a bevel gear 70. The bevel gears 70 are each driven by a cooperating bevel gear 71 secured to the end of a shaft 72 mounted for rotation in the transversely extending frame member 68. A suitable hand wheel 73 is provided for the purpose of conveniently rotating the shaft 72 and consequently it will be appreciated that rotation of the hand wheel 73 will serve to adjust the vertical position of the transversely extending connecting bar 66 and at the same time maintain this bar in fixed horizontal condition. Due to the fact that the housings 63 are permanently secured to the crossbar 66, it will be appreciated that the vertical position of these housings may be adjusted by means of rotation of the hand wheel 73. Journaled within each of the housings 65 is a lower idler pulley 75 and an upper pulley 16, which pulleys serve to mount a feed belt 77 which is driven by a horizontally extending shaft 78 to which the upper pulleys 16 are secured.

It will be appreciated that the hand wheel may be utilized for adjusting the vertical position of the housings so that the feed belt 77, as it passes over the lower pulleys 75, will serve to engage the upper surface of the padding material 15 as it passes through the press and serve to aid in feeding this material over the bed of the press. The vertical adjustment mechanism described above serves to provide convenient means for raising the housings 65 to facilitate removal of the upper die member 38.

The shaft 78 is driven by means of a pulley 80 secured to the outer end thereof over which passes a drive belt 81 which is driven by means of a sprocket wheel 82 journaled adjacent the delivery side of the press and operated by a sprocket chain 83 passing over a sprocket wheel 84. The sprocket wheel 84 has secured thereto a gear which cooperates with a rack 85 pivotally secured to the base frame of the blanking press at the point 86. The rack 85 is pivotally connected to the eccentric 46 at the point 87 and it will be seen that, as rotation of the shaft 45 takes place, the rack 85 will move arcuately about its pivot 86 and effect a rotation of the gear 84 and consequently the feed belts 77 which serve to feed material over the bed of the blanking press. It will be further appreciated that no movement of this feed mechanism will take place except at such times as the blanking press is driven and the respective parts are preferably so constructed and proportioned that movement of the rack mechanism will take place only at such times as the dies are in a position separated from each other. Due to the fact that the tubular housing 65 extends through suitable apertures in the upper die and the die frame, movement of the upper die will be entirely independent of the movement of these housings and, consequently, the feed belt 77 will be engaged with the surface of the padding material 15 at all times irrespective of the movement of the upper die mechanism.

The pinion engaged by the rack 85 meshes with a pinion 90 which is permanently secured to the shaft of the roller 21 and cooperates through a suitable gear train with a pinion 92 secured to the shaft of the roller 37. It will therefore be apparent that movement of the rack 85 serves to effect a simultaneous feeding rotation of the cooperating rollers 21 and 37 and the respective parts are so proportioned that this movement serves to feed a predetermined length of padding

material over the bed of the press at considerably greater speed than the rate at which the padding material is delivered to the conveyor belt 20 by means of the conveyor 10. The respective gears, racks, sprockets and belts are also so proportioned that the rate of feeding movement effected by the cooperating rollers 21 and 37 is substantially the same as the rate of feeding movement accomplished by the feed belt 77. Inasmuch as both of these feeding means are driven by the rack 85, it will be seen that the feeding action of both means will be synchronous and simultaneous and that neither one will operate except when both are driven.

It will be further appreciated that, as this relatively rapid feeding movement takes place, the central portion of the upper run of the belt 20 will be raised to a position where it will extend nearly directly between the rollers 19 and 30 and the rollers 21 and 37. The belt will be tensioned to this position due to the weight of the vertically movable roller 27 mounted in the guides 28.

A suitable source of light (not shown) is directed from one side of the apparatus and focused upon a photoelectric cell 95 located adjacent the central portion of the upper run of the conveyor belt when this belt is sagging to its lowest position. The photoelectric cell is connected by means of a suitable circuit with an electric switch mechanism 96 which serves to effect engagement of the clutch mechanism 63 when the light beam on the photoelectric cell 95 is interrupted.

The operation of the apparatus described above is substantially as follows: The continuous web of loosely felted, non-woven, fibrous padding material is continuously fed by means of the conveyor 10 onto the conveyor belt 20. It is assumed that the upper run of the belt is in a position above that shown in Fig. 4 and consequently the light beam focused upon the photoelectric cell 95 is not interrupted. Consequently, the blanking press and the mechanism for feeding the material therethrough are not in operation. As the feed of material from the conveyor 10 to the conveyor belt 20 takes place, it will be seen that the roller 19 at the rear end of the conveyor belt 20 is being constantly driven by the sprocket chain 11 and consequently the central portion of the upper run of the conveyor belt 20 will gradually sag downwardly until it reaches substantially the position shown in Fig. 4 of the drawings. When the central portion of the upper run of the conveyor belt 20 has sagged downwardly to this position, the light beam focused upon the photoelectric cell 95 will be interrupted and the switch mechanism 96 will consequently be actuated to engage the clutch 63. The engagement of the clutch 63 transmits drive of the motor 61 to the large gear 60, which serves to drive the blanking press through one complete cycle of operation. It will be appreciated that, due to the construction and arrangement of parts described above, at the beginning of the cycle of operation the upper die will be moved upwardly by the eccentric 46 and that rotation of this eccentric will serve to actuate the feed belts 77 and at the same time serve to rotate the rollers 21 and 37, rapidly feeding a predetermined length of padding material across the bed of the press. Due to the fact that the feed of the belts 77 and rollers 21 and 37 is considerably more rapid than the rate at which the belt is fed by means of the cooperating rollers 30 and 19, it will be appreciated that the upper run of the conveyor belt 20 will be

substantially raised, thus permitting the light beam to again impinge upon the photoelectric cell 95. After the feeding operation has been accomplished, the upper die of the blanking press 5 will move downwardly and blank out a section of padding material 100 of a configuration in accordance with the particular dies used, after which blanking operation the clutch mechanism 63 will be automatically disengaged until the upwardly sufficiently to cause a repetition of the cycle of movements above described.

The pinion which meshes with the rack 85 is preferably connected to its shaft by means of a 15 one-way clutch in order that the mechanism for feeding the material through the press including the rollers 21 and 37 and the feed belts 77 will not be operated except upon the upstroke of the press and consequently this feeding movement 20 will only take place during the time that the dies are engaged and therefore will take place in one direction only.

In order to feed the blanked-out sections 100 from the press, a pair of rollers 102 and 103 are 25 mounted near the delivery end of the press and are adapted to engage the material as it passes from the bed of the press. These rollers are geared for simultaneous rotation and are driven by the sprocket wheel 82 so that the feeding accomplished by these rollers will be synchronous with the feeding accomplished by the rollers 21 and 37 and the feed belts 77. Spaced slightly from the roller 103 is a roller 104 over which passes an endless conveyor belt 105 which may preferably be continuously operated to carry the blanked-out sections 100 away from the press. The marginal edges of the web 15 around the blanked-out sections will not have sufficient body to breach the gap between the roller 103 and the roller 104 and will consequently bend downwardly where they will be engaged by a pair of rollers 107 which feed this waste material against a rotary dis-integrating element 108 which may be driven by any suitable source of power and which 45 serves to break up this waste fibrous material and discharge the same into a housing 110. A large conduit 111 is connected to the housing and conveys fibrous material therefrom.

It will be appreciated that the above described 50 apparatus makes possible the substantially continuous delivery of a continuous web of loosely felted, fibrous material to the blanking press, and intermittent feeding of said material through the blanking press in order that no movement of the material will take place during the actual time 55 that a section of the material is blanked out, means for separating the waste material from around the marginal edges of the blanked-out sections and substantially continuously operated 60 means for conveying the blanked-out sections away from the blanking press.

The modified form of apparatus disclosed in Figs. 6 to 9, inclusive, has many features in common with the apparatus described above, but is 65 primarily designed for blanking out sections of upholstery material from a continuous composite strip. The material adapted to be operated upon by the apparatus shown in Fig. 9 comprises a strip of composite upholstery material 115 which 70 is formed, as is seen in Fig. 8, of a fabric backing layer 116, a fabric finish layer 117 and a layer of fibrous padding material 118 secured in position between the fabric layers. This padding material 118 is preferably secured in position by means 75 of longitudinal lines of stitching 119 which pro-

vide a plurality of tufts disposed side by side and extending longitudinally of the strip. The manner in which this composite strip of upholstery material is formed is described and claimed in applicants' assignee's prior co-pending application, Serial No. 67,862, filed Mar. 9, 1936.

The apparatus for blanking out sections of this material of suitable configuration to form includes a conveyor belt 120 which passes over a roller journaled on a shaft 121 to deliver the strip of upholstery material at a substantially continuous, uniform speed to a point adjacent the blanking press. The shaft 121 is journaled for rotation in a frame 122 which also has journaled therein a roller serving to support the rear end of a conveyor belt 123 serving to convey the material to the blanking press. As was described above, this roller at the rear end of the conveyor belt 123 is driven synchronously with the roller 121 by means of a suitable sprocket drive 124. A roller 126 preferably cooperates with the roller 121 to effect a positive feed of the upholstery material onto the conveyor 123. The front end of the conveyor 123 passes over a suitable roller 128 journaled for rotation in the base frame 129 of the blanking press. As was the case in apparatus described above, the belt 123 is substantially longer than is necessary to reach between the pulleys at the ends of this conveyor and intermediate its ends the belt passes over a roller 130 which is mounted for vertical movement in a pair of guide posts 131, one located at each of the lateral sides of the conveyor belt 123. The roller 130 has a shaft passing axially therethrough, which shaft at each end extends into a slot 132 formed in the vertically extending guides 131. The upper run of the conveyor belt 123 passes over the roller 130 and the roller 130 is preferably formed of sufficient weight to exert a constant downward pressure upon the upper run of this conveyor belt. The lower or return run of the conveyor belt 123 passing from the roller 128 extends downwardly over an idle roller 133 which may be journaled in the guide posts 131 and from the roller 133 this conveyor belt 45 passes upwardly over a stationary idle roller 134 and downwardly around a vertically movable idle roller 135 which is mounted for vertical movement in suitable guideways 136 formed as a part of the frame 122.

The intermittent feed mechanism utilized in connection with the blanking press is substantially identical with that described in connection with the embodiment of the invention shown in the preceding figures and like reference numerals 55 have therefore been used in designating the parts thereof. A switch box 140 is secured to one of the vertical guides 131 and this switch box has a switch arm 142 which projects into the path of the shaft of the roller 130 at a predetermined 60 point at the downward limit of movement of this roller. The switch 141 serves to close a circuit to the switch box 96 which effects engagement of the clutch 63 to effect, first, feeding of material through the blanking press, and, second, 65 blanking of a section of material from the strip. The dies utilized in this embodiment of the invention preferably serve to cut off only three sides of the upholstery section. The dies are preferably so formed that they trim the lateral sides 70 of each section to the predetermined desired form, such as is shown in Fig. 7, and trim the forward or top edge of the upholstery panel transversely across the entire width of the strip to separate next adjacent panels. The line of severance be- 75

5   between adjacent panels is, in practically all instances, a straight transverse line and consequently it is not necessary to use dies which blank out all sides of the panel, but is merely necessary to utilize dies for trimming the sides and transversely cutting across the strip. It will be appreciated that the ratio of the various parts comprising the feed mechanism may be carefully proportioned in order that the longitudinal length 10 of the panels formed by the machine will closely approximate the size desired.

10   While we have illustrated but two embodiments of the invention presented in this application, many other and further modifications may be 15 made, falling within the scope of the invention as defined in the subjoined claims.

We claim as our invention:

1. Apparatus of the class described comprising a continuously operated conveyor for feeding a continuous web of material toward a blanking press, a conveyor for feeding said web from said first mentioned conveyor into said blanking press, continuous means for driving one end of said second conveyor synchronously with said first conveyor, and intermittent means for driving the opposite end of said second conveyor in synchronism with the operation of said blanking press.

2. In a blanking press for blanking sections 30 from a continuous web of material, feed belts extending through the movable die of said press to engage the material stamped and to feed the same across the bed of the press.

3. In a blanking press, a stationary bed, a vertically movable die adapted to engage said bed and blank out sections of material from a web passed over said bed, means extending through said movable die adapted to engage material on said bed to feed said material across 40 said bed.

4. Apparatus of the class described comprising continuously operated means for feeding a web of material toward a blanking press, and a conveyor for feeding said web of material from said first mentioned means into the bed of said blanking press, one end of said conveyor being operated continuously and the other end being operated intermittently.

5. Apparatus of the class described comprising continuously operated means for feeding a continuous web of material toward a blanking press, a conveyor for feeding said web from said means into the bed of said blanking press, means for driving one end of said conveyor synchronously with said feeding means, and means for driving the opposite end of said conveyor intermittently to periodically feed a predetermined length of said web onto the bed of said press.

6. Apparatus of the class described comprising a blanking press having a vertically movable die, a stationary die adapted to cooperate with said movable die, feed means extending through apertures in said movable die adapted to engage

a section of material disposed upon said stationary die to feed the same transversely through said press, and means supporting said feed means independently of said movable die member.

7. Apparatus of the class described comprising continuously operated means for feeding a continuous web of material toward a blanking press, a conveyor belt for transferring said web from said means to said blanking press, a roller adjacent said blanking press serving to support and drive one end of said conveyor belt, intermittently actuated means for driving said roller, a second roller adjacent said feeding means and continuously operated means for actuating said second roller.

8. Apparatus of the class described comprising a continuously operated conveyor for feeding a strip of material toward a blanking press, a conveyor belt for transferring said strip from said continuously operated conveyor to said blanking press, means for driving the end of said conveyor belt adjacent said conveyor continuously and in synchronism therewith, and means for driving the end of said conveyor belt adjacent said blanking press intermittently.

9. Feeding mechanism for a blanking press comprising a pair of rollers, one adjacent said blanking press and one spaced therefrom, a conveyor belt carried on and driven by said rollers, means for driving the roller adjacent said blanking press relatively rapidly at predetermined intervals and means for driving the other roller relatively slowly but continuously.

10. Feeding mechanism for a blanking press comprising a pair of rollers one adjacent said blanking press and the other spaced therefrom, a conveyor belt carried on and driven by said rollers, means for intermittently driving said roller adjacent said blanking press, means for continuously driving the other of said rollers whereby to cause the upper run of said conveyor to sag downward intermittently and a vertically movable idle roller adapted to engage said conveyor belt to maintain the material fed in engagement therewith.

11. Feeding mechanism for a cutting means comprising a pair of rollers, one adjacent said cutting means and one spaced therefrom, a conveyor belt carried on and driven by said rollers, means for driving the roller adjacent said cutting means relatively rapidly at predetermined intervals and means for driving the other roller relatively slowly but continuously.

12. Apparatus of the class described comprising means for continuously feeding a continuous web of material toward a blanking press, means for intermittently operating said blanking press at predetermined intervals, and means for rapidly and periodically advancing said web into said blanking press in timed relation with the operation of said blanking press.

CLARENCE W. AVERY.
JAMES VEHKO.
